IRA B. HUMPHREYS, OF DENVER, COLORADO

PUMPING APPARATUS

Application filed August 19, 1924. Serial No. 732,938.

This invention relates to improvements in pumping apparatus, and more particularly to an apparatus for pumping wells in which a column of comparatively non-compressible fluid is substituted for the rigid sucker-rod construction now common in the art, and which column of fluid under pressure operates as the motive power to elevate a liquid to the point desired.

10 This invention is an improvement on that fluid actuated pump for which I made an application for Letters Patent on February 24, 1923, Serial No. 620,913. Like that particular pump, the present pump is double-acting. Among the particular advantages 15 of my present pumping apparatus are simplicity in construction and operation and ease of installation and removal for repair.

It has been found that the use of "sucker-rod pumps" is very unsatisfactory in deep wells. Particularly is this the case in the fields in Southern California and Texas, where many of the wells are of a depth of over four thousand feet.

25 Among the difficulties encountered with the use of the sucker-rod pump in deep wells, are that the rods very quickly wear in two, particularly at the joints of the rod section; and likewise wear holes in the well tubing, 30 and in many cases where it is believed there is considerable oil that might be recovered from the well, these pumps have produced about a pint of oil per stroke, and the number of strokes being limited by the peculiar construction of the walking beam, it will be obvious that very little oil is produced with such a device.

The principal object of this invention is to 40 produce a fluid operated pumping apparatus to elevate fluid from a source of supply that is simple in construction, with few parts, and which may easily be removed from the well should trouble develop thereon.

45 Another important object of this invention, like that of that particular application heretofore referred to, is to produce a pump in which any leak in the pump or in the valves connected therewith will result in the fluid 50 which is actuating the pump passing out

the discharge pipe from the pump and not passing into the oil sands.

An object of this invention is to provide a double-acting hydraulic pump for elevating fluids having a single valve of such a construction as to do the work of both the central valve and the working valve employed in that pumping mechanism of my copending application.

55 A further object of this invention is to provide a valve mechanism operable by differential pressure that it is impossible to stop in a dead-center position.

Another object of this invention is to provide a pump for elevating liquids which is of 60 relatively small diametrical dimensions so that it will be adapted to be disposed in an oil well or oil well casing of small diameter, and which pump is adapted to be actuated from a remote point by fluid under pressure.

65 Another object of this invention may be to provide a pump of comparatively high efficiency.

70 Other objects and advantages of this invention will be apparent from the following detailed description of a preferred embodiment thereof, as illustrated in the accompanying drawings.

75 In the drawings:

Fig. 1 is a diagrammatic side elevation of 80 an oil well illustrating the manner of pressure mechanism connected with a fluid operated pump, embodying this invention.

Fig. 2 is a side view, partly in section, of 85 a double-acting fluid actuated well pump embodying this invention.

Fig. 3 is a vertical mid-section of the 90 upper portion of the pump illustrated in Fig. 2, illustrating a manner of valve construction therefor.

Fig. 4 is a vertical mid-section of the lower portion of the double-acting hydraulic pump 95 illustrated in Fig. 2.

Fig. 5 is a horizontal section taken on the line 5-5 of Fig. 3.

Fig. 6 is a horizontal section taken on the line 6-6 of Fig. 3.

Fig. 7 is a horizontal section taken on the line 7-7 of Fig. 4.

Fig. 8 is a central mid-section of the 100

double-acting hydraulic pump illustrated in Fig. 2, showing the valve in the central position as moved thereto by the reciprocation of the pistons shown in the upper position.

Fig. 9 is a view similar to Fig. 8, illustrating the valve in the upper position and the pistons in the central position near the end of their downward stroke.

Fig. 10 is a central mid-section of the upper end of the hydraulic pump illustrated in Fig. 2, illustrating a modified form of connection of the pressure inlet and discharge pipes therewith.

Fig. 11 is a horizontal section taken on the line 11—11 of Fig. 10.

Fig. 12 is a horizontal section taken on the line 12—12 of Fig. 10.

Fig. 13 is a vertical section of a hydraulic oil well pump embodying a modified form of valve construction.

Fig. 14 is an enlarged vertical mid-section of the valve construction illustrated in Fig. 13.

Fig. 15 is a horizontal section taken on the line 15—15 of Fig. 14.

Referring to the preferred embodiment of this invention illustrated in the drawings, similar parts are illustrated by like numerals.

A represents a fluid storage tank; B represents a pressure mechanism for imparting pressure to the fluid pumped from the reservoir A; C represents a well casing; D represents a discharge pipe or casing for the pumping mechanism; E represents a high-pressure inlet pipe; F represents a unitary working control valve; G represents the valve housing or casing in which the valve F is actuated; H designates a hollow plunger rod which carries the pump pistons J and K within the pump cylinder or chamber L.

Attention is called to the fact that the pump mechanism illustrated in Figs. 3 and 4, put together, form a complete pump which is of comparatively short length, approximately 8 feet. It will be apparent from the drawings that the complete pumping mechanism may be assembled above the well in the cylinder L; attached to the valve housing G and lowered into the well within the discharge pipe D, which pipe D may have previously been lowered into the well in any desired manner, until the collar or ring 1 engages the inwardly extending flange 2 of the coupling 3. It will then be apparent that the pumping mechanism, with its attending pipes, is partially supported by the flange 2 and that in order to raise the pumping mechanism from the well it is only necessary to "pull" the inner pressure pipe E. The collar 1, is secured into the lower end of the nipple 10 by means of the threaded collar 101.

The valve casing G is screw-threaded to the lower end of the pressure pipe E as at 4, the said valve casing G being closed at its upper end by means of a cap 5. Ports 6 are

cut or otherwise positioned in the valve casing G and provide communication of the pressure pipe E with the valve mechanism F. Ports 7 are likewise positioned in the valve casing G and provide communication of the pump cylinder L with the valve F. 70 Fig. 8 illustrates the discharge ports from the valve F to the exterior of the valve casing G providing a discharge outlet from the fluid pump to the outside or fluid discharge pipe D.

The pump cylinder L is screw-threaded to the lower end of the valve casing or housing G as at 9. The pipe or nipple 10 is screw-threaded to the valve casing as at 11 and is for the purpose of directing the fluid under pressure to actuate the pump on its upper stroke. The piston K is mounted on the lower end of the hollow plunger rod H and carries at its lower end a ball valve 12, which ball valve 12 is maintained in the valve housing 13 by means of a valve shoe 14 of the ordinary construction. Packing 15 may be provided for the housing 13 so as to maintain a leak-proof connection with the pump cylinder L. Secured in position at the lower end of the pump cylinder L is a standing valve 16 of the ordinary construction.

Packing is positioned between the hollow plunger rod H and the cylinder L, preferably above the collar 1, which packing is positioned thereon by the following means. A packing ring 17 is secured to the cylinder L by means of a plurality of bolts or set screws 18 and packing 19 is positioned on the ring 17 and is held thereon by means of the packing ring 20 which is yieldingly forced downward by means of a helical spring 21, which helical spring 21 engages the ring 20 at one end and a ring 22, which ring 22 is secured to the cylinder L by means of a plurality of set screws 23. The advantage of having the packing 19 held in position in the manner heretofore described is that any wear thereof will be compensated for by the spring 21.

Packing is positioned between the cylinder L and the pipe 10 to provide a leak-proof joint at the lower end of the pipe 10 and is maintained in position by means of the packing ring 24 which rests on or is an extension of the collar 1. Packing 25 of any suitable material is positioned on the ring 24 and is held in position at its upper end by means of a packing ring 26 which packing rings and packing are of the proper size to be maintained in position by the heads of the set screws 23 heretofore described.

The pistons J and K are of any suitable construction and may be maintained in a tight relation with the cylinder L by means of piston rings, or packing 15 may be used in place of the piston rings, if such is desired.

Screw-threaded in the interior of the plunger rod H adjacent the upper piston J is a plug 28, and screw-threaded to the exterior of the rod H is a member 29, which

member 29 is cylindrical in form and bent inward at its upper end to form the circumferential shoulder 30. A spacing ring 31 is held in position on the top of the plugged hollow plunger rod H by any suitable means. A ring 32 rests on the spacing ring 31 and is adapted to engage one end of a helical spring 33, which helical spring is engaged at its other end by means of a ring 34, which ring 34 abuts the inwardly extending shoulder 30. Passing through the rings 32 and 34 is a valve actuating rod 35 which rod 35 has a head 36 at its lower end and a head 37 at its upper end. The heads 36 and 37 may be nuts screw-threaded thereto. The rod 35 extends upward from the hollow member 29 into the hollow valve stem 38 of the valve F, which valve F has a downwardly extending circumferential shoulder 39. Secured to or made a part of the valve stem 38 are the lower and upper valve heads 40 and 41, which valve heads may be as illustrated in Figs. 3, 8, 9 and 10 of the piston type, having piston rings 42 for packing mounted thereon to maintain a leak-proof joint with the valve housing G. One of the valve heads 40, is larger in cross sectional area than the other for the purpose that will hereafter be described.

The valve housing G is of smaller internal diameter at its upper end so as to provide a tight fit with the piston 41, which is of smaller external diameter than the piston 40. The piston 41 of the valve F is of approximately the same width as the port 8, while the piston 40 is likewise of approximately the same width as the horizontal extensions 43 of the port 6. The piston 40 is bevelled at its lower end 44 to closely fit the bevelled valve seat 45.

In the position of the valve illustrated in Fig. 3 the fluid under pressure from the pipe E passes through the port 6 through the extensions 43 thereof around the valve stem 38 and out through the port 7 and then passes through the channel 46 into the nipple 10 then through ports 48^a into cylinder L and exerts a pressure against the under side of the piston J elevating the same. The piston is then raised to the position illustrated in Fig. 8, at which time the extension 39 of the valve stem 38 engages the ring 34 and the said valve is caused to move upward to the position illustrated in Fig. 8, which is the top of the stroke of the pistons J and K. The valve is carried above the dead center position illustrated in Fig. 8 of the drawings, by inertia and thence on upward to the position illustrated in Fig. 9 by reason of the high pressure fluid acting on the lower face of the piston 40. With the valve in the position illustrated in Fig. 9 the fluid under pressure passes through the port 6, acts against the upper face of the piston J and forces the same downwardly until the head 37 of the rod 35 engages the inward extension 39 of the valve

stem 38, and on continued downward motion, the valve F is again returned to that position illustrated in Fig. 8 and downwardly past dead center by inertia. The moment the valve is below dead center position it is carried on downwardly, to the position illustrated in Fig. 3, by the high pressure fluid acting on the upper face of piston 40. At this time the high pressure fluid is also acting on the lower face of the piston 41 but due to the larger diameter of the piston 40, the valve is carried downwardly.

During the downward motion of the pistons J and K, the fluid sucked into the pump barrel or cylinder L on the upward stroke is exhausted through the hollow plunger rod ports 47 and the ports 46^a and passes upward through the port 7, and, as the valve is in the position illustrated in Fig. 9 during the downward stroke, the pumped fluid passes through the valve out through the port 8 and is discharged through the discharge pipe D. During the upward stroke of the pump, with the valve in the position illustrated in Fig. 3, the oil above the piston J passes through the ports 48 into the hollow valve stem 38 and hence out through the port 8 into the discharge pipe D. The upward stroke of the piston G is the suction stroke, and the standing valve is open so that oil is sucked from the well into the pump barrel or cylinder L. Pressure being exerted on the ball valve 12, the same will be closed during the upward stroke. During the downward stroke the ball in the valve 12 is unseated and the oil below the piston K is displaced into the hollow plunger rod H, forcing the oil therein out through the ports 47, 46^a and 46 through the valve F and is discharged from the well through pipe D.

The modification of this pump illustrated in Figs. 10, 11 and 12 is entirely similar to that modification described except for the connection of the pump with the pipes D and E. This modification of the pump will fit into a smaller casing than that modification heretofore described, but has the disadvantage of not being adapted to be pulled from the well on the pulling of a single strand of tubing. The inside of the pressure pipe E' is screw-threaded to the valve housing G' as illustrated at 49, and the discharge pipe D is screw-threaded to the valve housing G' as at 50, the valve housing G' being of slightly different structure than the valve housing G to eliminate direct communication of the pressure pipe E with the discharge pipe D, there being provided the horizontal extension 51, which is not found in the valve housing G; and the ports 8 are communicated with the discharge pipe D by means of the vertical passages 8' cored or drilled in the valve housing G'.

The modification of this pump illustrated in Figs. 13, 14 and 15 is entirely similar to

that construction illustrated in Figs. 1 to 9 inclusive, except for the valve mechanism embodied therein, which valve mechanism is of the following construction:

The valve casing G^* is bored larger than the external diameters of the valve heads 40^* and 41^* , to allow the positioning therein of the valve seats 52^* , 53^* and 54^* . The valve heads 40^* and 41^* comprise the pistons 55^* and 56^* and are fitted with ring heads 57^* and 58^* respectively. The seat 54^* is fixed, while the seats 52^* and 53^* are sliding valve seats. The ring heads 57^* and 58^* may be cast integral with the pistons 55^* and 56^* , or they may be made in the form of rings and fitted thereto. Recesses 59^* are provided in the pistons 55^* and 56^* to enable a free grinding of the said ring heads. The rings 57^* and 58^* may be bevelled as shown, or they may be formed spherical in shape, or they might be formed of square cross section; however, applicant believes that the bevelled or conical construction of these valve rings 57^* and 58^* to be the most practical and provides a better fitting connection with the valve seats; and with the said conical shape it is easier to grind than if the same were spherical or square.

The operation of this modified form of valve F^* is similar to that described in connection with that piston valve F , and is operated through the portion of its travel by means of motion transmitted thereto by the rod 35^* and is carried past the dead center by the difference in pressure exerted against the area of the fixed seat 54^* minus the area of the sliding seat 52^* or 53^* , depending upon which seat 52^* or 53^* the valve head 55^* is seated with.

Having fully described my invention it is to be understood that I do not wish to be limited to this preferred embodiment thereof which may obviously be varied in detail without departing from the spirit of the appended claims.

45 What I claim is:

1. A fluid pressure actuated well pump including an inner pipe and an outer pipe, a pumping mechanism suspended from the end of the inner pipe and embraced within the outer pipe, said pumping mechanism provided with a unitary control and working valve, a pressure mechanism communicating with one of said pipes above said pumping mechanism and providing liquid under pressure for actuating the pumping mechanism, and said valve controlling and directing the inlet of fluid pressure to the pumping mechanism and the discharge of the pumped fluid from the pumping mechanism, whereby said valve controls the operation of the pumping mechanism.

2. A fluid pressure actuated well pump including an inner pipe and an outer pipe, a pumping mechanism suspended from the end of the inner pipe and embraced within the

outer pipe, means for loosely supporting the pumping mechanism within the outer pipe, a pressure mechanism communicating with one of said pipes above said pumping mechanism and providing fluid under pressure for actuating the pumping mechanism, a unitary control and working valve forming a part of said pumping mechanism, and said valve positioned to control the inlet of the fluid pressure for actuating the pumping mechanism and the discharge of the pumped fluid from the pumping mechanism.

3. A fluid pressure actuated well pump comprising a pressure conveying pipe and a fluid discharge pipe, a fluid pressure supplying mechanism communicating with said pressure conveying pipe, a unitary working and control valve, a vertical pump barrel suspended from said unitary valve, an upper piston and a lower piston embraced within the said barrel, a hollow plunger rod connecting said pistons and acting on the upward stroke of said pump pistons as a conduit for the liquid pumped from the well, said pump barrel having communication with said pressure pipe and said discharge pipe, and said unitary valve controlling and directing the admission of the fluid pressure to the pumping mechanism and the discharge of the fluid pumped from the well.

4. A fluid pressure actuated well pump comprising a pressure conveying pipe embraced within a fluid discharge pipe, a pumping mechanism suspended from and in communication with both of said pipes, said pumping mechanism including a vertical pump barrel having therein upper and lower pistons connected by a hollow plunger, said plunger having communication with the pump barrel and serving on the upward stroke of said pump pistons as an outlet conduit for the pumped liquid from the well, a fluid pressure supplying mechanism communicating with the pressure conveying pipe, and means for alternately directing the fluid pressure against the upper and lower sides of one of the pistons for reciprocating the same and causing them to force liquid from the well up the discharge pipe.

5. A fluid pressure actuated well pump comprising a pressure conveying pipe embraced within a fluid discharge pipe, a pumping mechanism suspended from and in communication with both of said pipes, said pumping mechanism including a vertical pump barrel having therein upper and lower pistons connected by a hollow plunger, said plunger having communication with the pump barrel and serving on the upward stroke of said pump pistons as an outlet conduit for the pumped liquid from the well, a fluid pressure supplying mechanism communicating with the pressure conveying pipe, and a unitary valve for alternately directing the fluid pressure against the upper and lower

sides of one of said pistons and for controlling the path of flow of the pumped fluid from the well, whereby said inner valve controls the operation of the pumping mechanism.

5 6. A fluid pressure actuated well pump comprising an inner pipe and an outer pipe, a pumping mechanism suspended from one of said pipes and in communication with both of them, a pressure supplying mechanism communicating with and supplying fluid under pressure to one of said pipes above said pumping mechanism for actuating the pumping mechanism, said pumping mechanism including a sliding unitary working and control valve for controlling the discharge of pumped liquid from the pumping mechanism and the admission of fluid pressure to the pumping mechanism, a pump cylinder, a pair of pistons within said cylinder, said pistons actuated by said pressure fluid for the purpose of pumping and discharging liquid from the well, and means connecting said piston with said unitary valve for operating the same.

10 7. A fluid pressure actuated well pump comprising an inner pipe and an outer pipe, a pumping mechanism suspended from one of said pipes and in communication with both of them, a pressure supplying mechanism communicating with and supplying fluid under pressure to one of said pipes above said pumping mechanism for actuating the pumping mechanism, said pumping mechanism including a sliding unitary working and control valve for controlling the discharge of pumped liquid from the pumping mechanism and the admission of fluid pressure to the pumping mechanism, a pump cylinder, a pair of pistons within said cylinder, said pistons actuated by said pressure fluid for the purpose of pumping and discharging liquid from the well, and a lost motion connection between the pistons and said unitary valve for moving the valve throughout a portion of its travel.

15 8. A fluid pressure actuated well pump comprising an inner pipe and an outer pipe, a pumping mechanism suspended from one of said pipes and in communication with both of them, a fluid pressure supplying mechanism communicating with one of the pipes at a point above the pumping mechanism and supplying fluid pressure for actuating the pumping mechanism, said pumping mechanism provided with upper and lower pistons in separated relation and connected by a hollow plunger rod, said plunger rod acting as a conduit for the outlet passage of liquid pumped from the well on the upward stroke of the pistons, and means within the pipes and forming a part of the pumping mechanism to alternately direct the pressure against the upper and lower sides of one of said pistons to cause a reciprocation thereof for forcing liquid upwardly and outwardly from the well from one of said pipes.

9. A fluid pressure actuated well pump including elongated concentrically arranged pipes extending downwardly into the well, a pumping mechanism suspended from one of said pipes and in communication with both of them, a fluid pressure supplying mechanism communicating with one of said pipes at a point above the pumping mechanism and providing fluid under pressure for actuating the pumping mechanism, said pumping mechanism having a vertical pump cylinder with a pair of pistons mounted for reciprocation therein, and a unitary working and control valve forming a part of said pumping mechanism and alternately directing the fluid pressure above and below one of said pistons and simultaneously directing the path of flow of the pumped fluid from the well upwardly through one of said concentrically arranged pipes.

70 10. A fluid pressure actuated well pump comprising an inner pipe and an outer pipe, a pumping mechanism suspended from the inner pipe, a fluid pressure supplying mechanism communicating with one of said pipes at a point above said pumping mechanism and supplying fluid under pressure for actuating the pumping mechanism, and a unitary valve mechanism within said pumping mechanism for continuously directing the fluid pumped by the pumping mechanism upwardly and outwardly through one of said pipes and simultaneously directing the fluid pressure to actuate said pumping mechanism.

75 11. A fluid pressure actuated well pump comprising an inner and an outer pipe, a double acting pumping mechanism suspended from the inner pipe, a fluid pressure supplying mechanism in communication with the inner pipe at a point above said pumping mechanism for delivering fluid under pressure to the pumping mechanism, said pumping mechanism including a unitary working and control valve placed to control the admission of the pressure fluid to the pumping mechanism and the discharge of fluid pumped by said pumping mechanism upwardly and outwardly through the outer pipe.

80 12. A deep well pump of the character herein described, including a pump barrel having therein a piston, inlet and outlet pipes communicating with said pump barrel, a liquid pressure supplying mechanism communicating with the inlet pipe for actuating said piston, a fluid inlet and a fluid outlet, a valve having two heads of differential diameters, valve seats for said heads, movable means in conjunction with said valve seats for compensating for wear and said single valve controlling said fluid inlet and said fluid outlet for controlling the operation of the pump.

85 13. A deep well pump of the character

130

herein described, including a pump barrel having therein a piston, inlet and outlet pipes communicating with said pump barrel, a liquid pressure supplying mechanism communicating with the inlet pipe and supplying liquid pressure to the said pump barrel for actuating said piston, a fluid inlet and a fluid outlet, a valve controlling said fluid inlet and outlet for controlling the operation of the pump, said valve comprising a hollow valve stem having at its ends valve heads of differential diameters, said hollow stem in communication with the pump cylinder and adapted to act as an outlet therefor during the upward stroke of the piston, and a stationary valve seat for one of the valve heads and a movable valve seat for the other valve head, whereby said valve seats compensate for wear.

14. A deep well pump of the character herein described, including a pump barrel having therein a piston, inlet and outlet pipes communicating with said pump barrel, a liquid pressure supplying mechanism communicating with the inlet pipe and supplying liquid pressure thereto for actuating said piston, a valve casing positioned above said pump barrel, said casing provided with an inlet port and an outlet port communicating with the interior of said casing, a valve mechanism within said casing provided with a hollow valve stem having at its ends heads of differential diameters, said hollow stem in communication with the pump barrel and the interior of the valve casing and adapted on the upward stroke of the piston to act as a discharge outlet for the pump barrel, said valve adapted for reciprocation and controlling said inlet and said outlet ports for controlling the operation of the pump, a stationary valve seat within the valve casing for one of said heads and a movable valve seat within the casing for the other valve head, whereby said valve seats compensate for wear.

15. A unitary control and working valve for a deep well pump of the character herein described, comprising a valve rod provided with spaced pistons having differential diameters, a pressure supplying mechanism for supplying liquid under pressure acting against said pistons, means to reciprocate said pistons, and the differential in pressure upon the differential heads serving to hold said pistons against reciprocation after they have been moved to their respective positions.

16. A fluid pressure actuated well pump including an inlet pipe and an outlet pipe, a pumping mechanism having a pump barrel in communication with and forming a continuation of said inlet pipe, a pump piston in said pump barrel, a pressure mechanism communicating with and delivering fluid under pressure to the inlet pipe for actuating said piston, and a unitary valve for said pumping mechanism positioned to alternate-

ly direct the pressure fluid above and below said piston and to direct the discharge of pumped fluid up said outlet pipe.

17. A fluid pressure actuated well pump including an inner pipe and an outer pipe, a pumping mechanism having a pump barrel in communication with and forming a continuation of said inner pipe, a piston in said pump barrel, means carried by the outer pipe for removably supporting the pumping mechanism, a pressure mechanism communicating with and supplying fluid under pressure to the inner pipe for actuating said piston, and a unitary valve for said pumping mechanism positioned and functioning to alternately direct the pressure fluid above and below said piston and to direct the discharge of pumped fluid up the outer pipe.

18. A fluid pressure actuated well pump including a pressure conveying pipe and a discharge pipe, a pumping mechanism having a pump barrel and a piston therein, said barrel in communication with and forming an extension of said pressure pipe, a pressure mechanism in communication with and delivering liquid under pressure to said pressure pipe, and a valve positioned to direct the pressure fluid to alternately raise and lower said piston and to direct the fluid pumped by said piston up said discharge pipe.

19. A fluid pressure actuated well pump including an inner and an outer pipe, a pump barrel having therein a pair of pistons in spaced relation and connected by a hollow plunger, a unitary working and control valve, a casing for said valve having communication with both of said pipes and the pump barrel, said hollow plunger communicating with the pump barrel and with the well, one of said pistons adapted to lift fluid from the well into said hollow plunger and pump barrel, the other of said pistons adapted to pump the fluid from said pump barrel, a pressure mechanism for supplying liquid under pressure to said valve casing, and said unitary valve positioned and constructed to direct said pressure liquid to reciprocate said pistons and to direct the discharge of pumped fluid from the pump barrel through one of said pipes.

20. A fluid pressure actuated well pump including an inner and an outer pipe, a pump barrel having therein a pair of pistons in spaced relation and connected by a hollow plunger, a valve casing having communication with both of said pipes and the pump barrel, a unitary working and control valve mounted for reciprocation in said casing, a connection between said valve and said pistons for reciprocating said valve, said hollow plunger communicating with the pump barrel and with the well, one of said pistons adapted to lift fluid from the well into said hollow plunger and pump barrel, the other of said pistons adapted to pump the fluid from said

- pump barrel, a pressure mechanism for supplying liquid under pressure to said valve casing, and said unitary valve automatically shifted by its connection to the pistons and said liquid under pressure to direct said in- 5
 5 let pressure fluid to reciprocate said pistons and to direct the discharge of pumped fluid from the pump barrel through one of said pipes.
21. A deep well pump of the character 10 herein described, including a pump barrel having therein a piston, a fluid pressure inlet pipe and a discharge pipe for the pumped fluid both of said pipes communicating with the pump barrel, a liquid pressure supplying 15 mechanism communicating with the pressure inlet pipe and supplying liquid under pressure to said pump barrel for actuating said piston, a unitary working and control valve including a valve housing forming a part of 20 the conduits constituting said pressure inlet and fluid outlet pipes, said housing having communication with said pump barrel, a valve mounted for reciprocation in said housing and having a pair of heads of differential 25 diameter in spaced relation, means for reciprocating the valve heads to control and direct the inlet and outlet of fluid to and from said pump barrel, and said valve being held 30 in position by the differential pressure of the liquid pressure present in the valve housing between the valve heads.
22. A deep well pump of the character 35 herein described, including a pump barrel having therein a piston, a fluid pressure inlet pipe and a pumped fluid outlet pipe both of which communicate with said pump barrel, a liquid pressure supplying mechanism communicating with the inlet pipe and supplying 40 liquid pressure thereto for delivery to the pump barrel for actuating said piston, a unitary working and control valve mounted for reciprocation within a casing, said casing constituting a by-pass of the pressure in- 45 let pipe and a conduit for connecting the outlet pipe with the pumping mechanism, said casing having a port communicating with the inlet pipe, said control valve comprising a stem carrying thereon in spaced 50 relation pistons of differential diameters, means for moving said valve a predetermined distance within said casing to permit one of the valve pistons to open the pressure inlet port above or below said valve piston, where- 55 by the fluid pressure is permitted to enter the valve casing above or below the valve piston to move it further through the differential pressure present between the spaced pistons of the valve, and said valve through 60 its movement automatically diverting the pressure fluid above and below the pump piston and directing the flow of discharge fluid from the pump barrel, for the purpose described.
23. A valve mechanism for fluid pressure 65 operated devices comprising a hollow valve stem having at its ends two heads of differential diameters, valve seats for said heads, and movable means in conjunction with said valve seats for compensating for wear.
24. A valve mechanism for fluid pressure 70 operated devices comprising a valve casing having an inlet and an outlet port therein, a valve comprising a stem having at its opposite ends heads of differential diameters, said stem and heads reciprocable within said casing and movable valve seats within said casing for one of said valve heads.
25. A valve mechanism for fluid pressure 75 operated devices comprising a valve casing having mounted therein for reciprocation a rod having thereon two heads, said rod being hollow and passageways through said heads communicating with and forming a continuation of said hollow rod opening, and valve 80 seats in said casing for said heads.
26. A valve mechanism for fluid pressure 85 operated devices comprising a valve casing having mounted therein for reciprocation a hollow rod having thereon two heads of differential diameters, passageways through 90 said heads communicating with and forming a continuation of said hollow rod, and valve seats in said casing for said heads.
